DESIGN FOR A SEWING MACHINE FRAME

James H. Van Vorst, Dumont, N. J., assignor to
Willcox & Gibbs Sewing Machine Company,
New York, N. Y., a corporation of New York

Application February 4, 1942, Serial No. 105,625

Term of patent 14 years

To all whom it may concern:

Be it known that I, James H. Van Vorst, a citizen of the United States, residing at Dumont, in the county of Bergen and State of New Jersey, have invented a new, original, and ornamental Design for a Sewing Machine Frame, of which the following is a specification, reference being had to the accompanying drawing, forming a part thereof, and in which—

Figure 1 is a front elevational view of the sewing machine frame embodying my new design;

Fig. 2 is a top plan view of the design;
Fig. 3 is a left side elevational view of the sewing machine frame embodying my design;
and

Fig. 4 is a right-hand side elevational view.
I claim:

The ornamental design for a sewing machine frame, substantially as shown.

JAMES H. VAN VORST.
